UNITED STATES PATENT OFFICE.

JOSEPH V. ROBINSON, OF BRANFORD, CONNECTICUT.

AUTOMATIC TRAIN-PIPE COUPLING.

1,245,798.

Specification of Letters Patent.

Patented Nov. 6, 1917.

Application filed October 13, 1914, Serial No. 866,473. Renewed September 13, 1917. Serial No. 191,314.

To all whom it may concern:

Be it known that I, JOSEPH V. ROBINSON, a citizen of the United States, and resident of Branford, county of New Haven, State of Conn., have invented certain new and useful Improvements in Automatic Train-Pipe Couplings, of which the following is a specification.

Among the objects of my invention are to produce an improved support for train pipe coupling heads which will offer the minimum resistance to coupled heads under all conditions of service, thereby greatly minimizing the strain which tends to separate coupled heads causing leaks, and to provide an improved means for positively locking such heads together.

To this end my invention consists in the combinations, improvements and constructions hereinafter described, pointed out in the appended claims, and illustrated in the accompanying drawings, in which:

Figure 1, is a side elevation of my improved train pipe coupling support and locking device.

Fig. 2, is a front face view thereof.

Fig. 3, is a rear view of the coupling head, taken substantially on the line 3—3 of Fig.

4. In this view the spring is omitted.

Fig. 4 is a horizontal section of my improved support and locking device. In this view the locking member is shown in the service position.

Fig. 5, is a plan view of the locking member.

Fig. 6, is a face view of the plate 16 of my improvement.

Fig. 7, is a face view of the base or bracket of my invention, and

Fig. 8, is a rear view thereof showing the stop 25.

Referring to the drawings: I attach my improvement to the usual car coupler 10 as by bolts 11 which pass through the upper extremity of a split base or bracket A, the lower extremity of which is cup shaped, as shown at 12, and has therein a convex partly spherical seat 13 provided with a flared opening 14 corresponding to the shape of the stem 15. A plate 16 having a concave partly spherical socket 17 and having also an annular seat or bearing 18 for a spring, is mounted on said convex seat for universal movement. A coupling head B positioned in front of the base A is perforated as at

19 and is provided with guiding prongs 20, one of which is perforated as at 21.

A fluid conduit C, the walls of which extend rearwardly of the coupling head B and parallel with the longitudinal axis thereof for a short distance and thence flare laterally of the coupling head, as shown at 22, extends through the coupling head and carries a gasket 23. A stem 15 of less diameter than the diameter of the conduit and rectangular in cross section and of different material from the material of the conduit C, is suitably connected with the latter, preferably by casting the latter around it, and extends rearwardly thereof through the opening 14 in the base A and operates to prevent undue rotation of said coupling head. The stem is threaded at 24 to receive a stop or nut 25 which bears against the rear flat face 26 of the base A and serves to limit the forward movement of the coupling head B, and cooperates with the spring D to support the head.

A locking device E having a perforated head 27 surrounds said stem and is provided with an annular bearing 28 and a vertically extending groove 29, which is mounted on a complementary bearing or rib 30 on the rear face of the curved portion 31 of the conduit C. On the side of the longitudinal axis of said coupling head B, opposite the side on which is pivoted the head 27 of the locking member E, such member is provided with an arm 32 a portion 33 of which projects forwardly of the conduit into the perforation 21 of one of the guiding prongs 20 of the coupling head B.

The spring D is interposed between the locking device and the plate 16 and rests in the seat 18 of the plate and on the bearing 28 of the locking member E and operates to support said head and place it under pressure and to shift the arm 32 of the locking device into the service position with a varying force depending upon the extent of compression of the spring.

When two automatic train pipe couplings provided with my improvement meet in the act of coupling, the guiding prongs 20 aline the heads and bring the gaskets 23 into accurate register. Immediately preceding final engagement the heads engage the tapered face 33 of the arms 32 and force the arms outwardly against the tension of the spring D, which allows proper seating of the heads.

one upon the other. Further movement of the cars will compress the spring D, virtually the full force of which is then localized on the arm 32 and the locking connection between the arm and the companion coupling head 34, see Fig. 4.

No claim is herein made to the novel features of the particular form of supporting means for a train pipe coupling illustrated 10 and described. The right is reserved to present claims for such novel features in a divisional application.

Having thus described my said invention, what I claim as new and desire to secure by 15 United States Letters Patent is:

1. In an automatic train pipe coupling, the combination of a coupling head provided with a perforated forwardly extending guiding prong, a fluid conduit for said head, means for locking the head to a companion head, such means comprising a member having a base pivoted relative to said conduit on one side of the longitudinal axis of said coupling head and extending across 20 to the opposite side of said axis, an arm connected with said member and projecting forwardly thereof into the perforation of said guiding prong, and a spring for actuating said locking means.
2. In an automatic train pipe coupling, the combination of a coupling head having a perforated guiding prong, a base, a stem extending rearwardly of said head through said base, an arm pivoted on one side of the longitudinal axis of said head and extending across to the opposite side of such axis in a plane substantially parallel with the plane of said coupling head and thence projecting forwardly into the perforation of said guiding prong, a bearing on said arm, a plate mounted on said base for universal movement and having a seat, and a spring interposed between said arm and said base and resting in said bearing and on said seat 30 for rotating said arm upon its pivot to lock said coupling head to a companion head.
3. In an automatic train pipe coupling, the combination of a coupling head having a perforated guiding prong, a base, a fluid conduit, a stem extending rearwardly from said conduit through said base, an arm pivoted on said conduit at one side of the longitudinal axis of said head, and extending across to the opposite side of such axis 40 and thence projecting forwardly into the perforation of said guiding prong, said arm being provided with a perforated head through which said stem extends, a bearing on said arm, a plate mounted on said base for universal movement relative thereto and having a seat, and a spring interposed between said arm and said base and resting in 50

said bearing and on said seat for rotating said arm upon its pivot in substantially the horizontal plane to cause the arm to lock 65 said coupling head to a companion head.

4. In an automatic train pipe coupling, the combination of a coupling head having a perforated guiding prong, a base, a stem extending rearwardly of said head through 70 said base, an arm pivoted on one side of the longitudinal axis of said head and extending across to the opposite side of such axis and thence projecting forwardly and being provided with a portion which extends into 75 the perforation of said prong, and a spring acting against said arm for shifting the same to the service position and for maintaining said arm in such position under various pressures depending upon the extent 80 of the compression of said spring.

5. In an automatic train pipe coupling, the combination of a perforated coupling head having a perforated guiding prong, a fluid conduit mounted in the perforation of 85 said head and extending therethrough and carrying a gasket, said conduit being curved laterally of said head at the rear thereof, a base having a perforated cup shaped extremity, a stem projecting from the curved 90 portion of said conduit rearwardly through the perforation in said base, a partly spherical seat in the extremity of said base and surrounding said stem, a plate having a partly spherical socket embracing said seat 95 and having also an annular bearing, a bearing on the curved portion of said conduit, a locking member having a perforated head which head surrounds said stem and rests in the bearing on said conduit on one side 100 of the longitudinal axis of said coupling head, an arm connected with the head of said member and lying on the side of the longitudinal axis of said coupling head opposite the side on which the head of said member 105 is pivoted and projecting forwardly of said conduit into the perforation of said guiding prong, a spring interposed between said member and said plate and mounted in the annular bearing of the plate and acting 110 against said member for yieldingly sustaining said coupling head and for actuating said member, and a stop on the rear end of said stem for engaging the rear face of said base to limit the forward movement of said coupling head and for co-operating with said spring to support said coupling head.

In testimony whereof, I have hereunto set my hand in the presence of two witnesses.

JOSEPH V. ROBINSON.

In the presence of—

KATHERINE V. BOSWELL,
M. C. SHERIDAN.
